ROUGHING HEAD

William C. Card, Jr., Winthrop, Mass., assignor
to Compo Shoe Machinery Corporation, New
York, N. Y., a corporation of Delaware

Application January 4, 1934, Serial No. 705,181

9 Claims. (Cl. 69—1)

This invention relates to a structurally and functionally improved roughing head and/or element, which may be capable of use in various associations, but is primarily intended to be employed in the manufacture of shoes and similar articles, and especially by means of which the outsoles of shoes may be roughened.

It is an object of the invention to provide an article of this character by means of which uniform and rapid results may be obtained.

A further object of the invention is that of constructing roughing elements which will have a far longer effective life than similar elements as heretofore provided.

15 A still further object is that of constructing a roughing element which, if desired, may be reconditioned to have a further useful life after its surfaces have once become dulled.

Another object is that of providing a head which will adequately support various types of roughing elements, but which is primarily intended to be utilized in connection with elements embodying a construction as taught by the present invention. Regardless, however, of the type of element which is employed, a head constructed in accordance with the present invention will serve to rigidify and strengthen the individual elements aside from the fact that the depth of roughing may be accurately gauged by the use of this head.

30 An additional object is that of furnishing a roughing element which in itself will embody a structure extremely resistant to accidental breakage or distortion.

35 Among still further objects of the invention are those of providing a roughing head and/or element which will individually and collectively include extremely simple structures, embracing relatively few and rugged parts, these parts being capable of use by comparatively unskilled labor, and capable of being produced at relatively low cost. Additionally, these parts may be quickly assembled, and, when so assembled, will provide a unitary and mutually cooperative structure capable of use over long periods of time with freedom from difficulties. Moreover, when it does become necessary to renew or replace any of the elements of the assembly, this may be done with the expenditure of only minimum effort and time.

With these and other objects in mind, reference is had to the attached sheet of drawing illustrating practical embodiments of the invention, and in which—

55 Fig. 1 is a partly sectional front view of a

roughing machine and showing a head and elements constructed in accordance with the teachings of the present invention associated therewith;

Fig. 2 is a side elevation of such head and elements;

Fig. 3 is a bottom plan view of the unit as illustrated in Fig. 2;

Fig. 4 is a sectional side view taken along the lines 4—4 as indicated by the arrows in Fig. 3; 10

Fig. 5 is a side elevation of one of the roughing elements; and

Fig. 6 is an enlarged end view thereof.

Referring primarily to Fig. 1, it will be noted that in this view there has been illustrated one 15 form of roughing machine. This is, of course, merely for the purpose of showing the invention in such association. It is obvious that any other form of machine may utilize the teachings of the present invention.

20 Thus, in Fig. 1 the numeral 10 indicates a table, which may be supported as at 11, and which is formed with an opening through which sole-engaging and work-supporting rollers—respectively indicated at 12 and 13—may extend. 25 Above the table a feeding roller 14 may be provided, and these rollers engage between them a sole 15, to be roughened. Extending preferably above the table is a support 16, for a rotary spindle 17, and this spindle supports and drives 30 the head, generally indicated at 18. Adjacent the head a sole-guide 19 may be mounted. It will, of course, be appreciated that suitable mechanism (not shown) is provided for operating the feeding roll 14, rotating the spindle 17, 35 and otherwise driving the operating parts of the machine.

Now referring to Figs. 2 to 4, it will be noted that a roughing head constructed in accordance with the teachings of the present invention may 40 include a cylindrical body 20, formed with two annular and concentric series of bores. The individual bores of one series are preferably disposed in staggered relationship with respect to adjacent bores of the other series, these bores 45 receiving roughing elements or needles, to be hereinafter described. The length of the body 20 is, of course, less than the length of the needles or elements, but should, in any event, be adequate to firmly support the needle bodies. Moreover, while the body of the head may be secured to the spindle 17 in any desired manner, it is preferable that this be accomplished by forming such body with a central bore or well 21, 50 which may be screw threaded, as at 22, to re- 55

ceive a similarly threaded stud or projecting part carried by the spindle. The bore 21 may be continued and, if desired, reduced, to extend through to the lower face of the body 20. This extension may also be screw threaded to receive the threaded stem 23 of a gauge plate 24. In this manner it is obvious that the distance between the plate and the outer face of the body 20 may be adjusted and, when such adjustment has once been achieved, the parts may be locked against further movement by a nut 25 encircling the stud.

As has been especially shown in Fig. 3, the gauge plate 24 is formed with an annular series of openings to align with the innermost series of bores formed in the body 20, and this plate is, in the present exemplification, formed with a series of notches in its edge, which notches align with the outermost series of bores formed in such body. While the latter construction is, of course, not essential, it is, according to many aspects, preferable, for the reason that it is desirable to have the roughing elements or needles of the outermost series a major distance to one side of the spindle axis, and by having these notches it is, of course, unnecessary to have the gauge plate extend beyond the face of the body 20.

As afore brought out, a head of this construction may be utilized in connection with various types of roughing needles or elements. However, it is preferred that it be employed in connection with elements or needles of a construction such as taught in the present specification, it being also preferred that such novel needles or elements be utilized with a head of this type. As shown, especially in Figs. 4 and 5, these needles include bodies 26, which may pass through the bores formed in the head 20, and which are of such length that they will extend beyond the upper face of this body and below the lower face of the gauge plate. At their upper ends these elements are formed with heads 27, which prevent the needles from falling through the bores, and at their lower ends the needles terminate in points which are developments of surfaces 28 extending inwardly and angularly with respect to each other. These surfaces may, of course, be formed by grinding and, as shown, may be three in number. However, regardless of their number, it will be seen that along the lines of juncture of adjacent surfaces, edge portions are formed which, in conjunction with the points, will effectively cooperate with the surface of the sole or other work. Also, due to the provision of these surfaces, a rigidifying factor is embodied in the needles which will tend materially to strengthen the same and reduce the liability of breakage.

In use it will be appreciated that if the head and elements are constructed as illustrated, an operator will primarily adjust the gauge plate to lie in a plane such that the ends of the needles or roughing elements will project beyond such plate to just the desired extent. Thereafter, he will secure the plate against movement and associate with the head thus provided a suitable number of needles in the manner best shown in Fig. 4. The extended portion or part carried by the spindle 17 will now be introduced in the bore 21, and the parts will be relatively turned until they assume positions locked with respect to each other. In this connection it will be noted that the spindle 17 may carry a flanged member 29, which will bear against the heads of the needles

to prevent any axial shifting thereof. The machine is now ready for operation, and if work is fed through the same and the spindle rotated, the surface of the work will be effectively roughened. Incident to the provision of the head 27, absolute alignment between the several needle points will be assured. As shown in the drawing, the length of the several needles used on a given head, from their heads 27 to their points, is substantially identical. Since the heads 27 seat against the flat upper surface of the needle head 20, it follows that the points of the needles will occupy substantially the same horizontal plane. This provides an especially easy and effective way of securing proper relationship of the needle points, and this relationship may readily be maintained even during subsequent resharpening of the needles since the nature of their points makes it relatively easy to resharpen each needle to exactly the same length as every other needle used on a given head. Also in view of the angular surfaces 28 it will be found that the work may be performed with greater facility and that the quality of the work will be more satisfactory, aside from the fact that the roughing elements will remain in proper useful condition for a longer period of time, and, when once dulled, may, if desired, be reground. Due to the provision of the gauge, the depth of the roughing may be accurately regulated, and, consequently, gouging and pulling of the sole material is prevented. This is aside from the fact that the gauge acts as a guard which prevents chattering or play on the part of the needles with respect to each other or with respect to the head.

Thus, among others, the several objects of the invention as specifically afore noted, are achieved. It will be understood that numerous changes in construction and rearrangements of the parts might be resorted to, without departing from the spirit of the invention as defined by the claims.

Having thus fully described the invention, what is claimed as new and desired to be protected by Letters Patent is:

1. In combination, a rotatable head having a bore therein to receive a roughing needle, and a guard plate secured to said head, said plate being formed with a notch in line with said bore and snugly accommodating said needle.

2. In combination, a head formed with a plurality of concentric bores to receive roughing elements, a plate connected to said head, said plate being formed with openings in line with one of said series of bores and with notches in line with another series of said bores.

3. A sole roughing device comprising a vertically rotatable body, a driving spindle therefor, a plurality of rigid roughing needles fixedly supported for a substantial portion of their lengths in said body, said needles having pointed lower ends extending below said body and terminating in a common plane, and a gauge member mounted on and extending below said body, said member being located entirely interiorly from the outermost of said needles.

4. A sole roughing device comprising a vertically rotatable body, a driving spindle therefor, a plurality of rigid roughing needles fixedly supported for a substantial portion of their lengths in said body and having pointed ends extending below said body and terminating in a common plane, a supporting plate having openings individually accommodating said needles near their pointed ends, and means adjustably mounting

said plate on said body for movement toward and from the latter.

5. A sole roughing device comprising a hollow, interiorly threaded body having a plurality of vertical bores therethrough, a driving spindle screwed into said body, a plate member having a central stem adjustably screwed into the lower end of said body and having a plurality of openings severally registerable with said bores, a plurality of rigid roughing needles each extending downwardly through one of said bores and beyond a registered opening of said plate member, and means fixing said needles against vertical movement with respect to said body.

15. 6. A sole roughing device comprising a hollow, interiorly threaded body having a plurality of vertical bores therethrough and having a flat upper surface, a plurality of headed roughing needles of substantially identical lengths extending 20 through and beyond said bores with their heads overlying the upper ends thereof, a driving spindle screwed into said body, and a flange fixed to said spindle in position to seat over said needle heads to hold them against said flat surface.

25. 7. A sole roughing device comprising a vertically rotatable body having a plurality of vertical bores therethrough and having a flat upper surface, a plurality of straight, rigid, headed roughing needles of substantially identical lengths ex-

tending through and below said bores with their heads resting against said flat upper surface, means fixedly holding said needle heads against said surface, and a plate mounted on and spaced from said body and supporting said needles adjacent their lower ends.

8. A sole roughing device comprising a rotatable body having a plurality of bores extending therethrough, a plurality of rigid roughing needles extending through and beyond said bores, 10 and a plate spaced from and mounted on said body, said plate having interiorly located holes individually accommodating the ends of some of said needles and having peripheral notches accommodating the ends of others of said needles. 15

9. A sole roughing device comprising a rotatable spindle, a needle head mounted on the end of said spindle for rotation therewith, said needle head having a flat upper surface and a plurality of vertical bores therethrough, a plurality 20 of roughing needles of substantially identical lengths extending through and beyond said bores, said needles respectively being snugly supported in said bores along a substantial portion of their lengths and each having an enlarged head overlying the upper end of its bore, and a flange fixed to said spindle in position to seat over said needle heads to hold them against said flat surface. 25
